AUTOMOBILE ORNAMENT

Walter Stanley Silka, Detroit, Mich.

Application August 3, 1954, Serial No. 31,724

Term of patent 14 years

(Cl. D14—6)

I claim:

The ornamental design for an automobile ornament, as shown.
